US0D1034501S

(12) **United States Design Patent** (10) Patent No.: **US D1,034,501 S**
(45) Date of Patent: ** Jul. 9, 2024

(54) **ELECTRONIC DEVICE**

- (71) Applicant: **Samsung Electronics Co., Ltd.**, Suwon-si (KR)
- (72) Inventors: **Seung-Ho Jang**, Suwon-si (KR); **Da-Wi Lee**, Suwon-si (KR); **Jong-Bo Jung**, Suwon-si (KR); **Mi-Ri Lee**, Suwon-si (KR)
- (73) Assignee: **Samsung Electronics Co., Ltd.**, Suwon-si (KR)
- (**) Term: **15 Years**
- (21) Appl. No.: **29/844,956**
- (22) Filed: **Jul. 1, 2022**

Related U.S. Application Data

- (62) Division of application No. 29/770,227, filed on Feb. 10, 2021, now Pat. No. Des. 966,250.

(57) **CLAIM**

We claim the ornamental design for an electronic device, as shown and described.

DESCRIPTION

FIG. 1 is a rear perspective view of an electronic device showing our new design in accordance with a first embodiment;

FIG. 2 is a rear view thereof;

FIG. 3 is a front view thereof;

FIG. 4 is a left-side view thereof;

FIG. 5 is a right-side view thereof;

FIG. 6 is a top view thereof;

FIG. 7 is a bottom view thereof;

FIG. 8 is a front perspective view thereof;

FIG. 9 is a rear perspective view of an electronic device showing our new design in accordance with a second embodiment;

FIG. 10 is a rear view thereof;

FIG. 11 is a front view thereof;

FIG. 12 is a left-side view thereof;

FIG. 13 is a right-side view thereof;

FIG. 14 is a top view thereof;

FIG. 15 is a bottom view thereof;

FIG. 16 is a front perspective view thereof;

FIG. 17 is a rear perspective view of an electronic device showing our new design in accordance with a third embodiment;

(Continued)

FIG. 18 is a rear view thereof;
 FIG. 19 is a front view thereof;
 FIG. 20 is a left-side view thereof;
 FIG. 21 is a right-side view thereof;
 FIG. 22 is a top view thereof;
 FIG. 23 is a bottom view thereof; and,
 FIG. 24 is a front perspective view thereof.
 The evenly-dashed broken lines in the figures depict portions of the electronic device which form no part of the claimed design.
 The pair of closely spaced dot-dash waved lines in the figures indicate the appearance of any portion of the article between the break lines forms no part of the claimed design.

The pair of closely spaced dot-dash waved lines in the figures indicate the appearance of any portion of the article between the break lines forms no part of the claimed design.

1 Claim, 24 Drawing Sheets
